UNITED STATES PATENT OFFICE.

EDWIN CALDWELL, OF NEW YORK, N. Y.

SMOKING IMPLEMENT.

Application filed July 29, 1926. Serial No. 125,637.

This invention relates to smoking implements such as pipes, and cigar and cigarette holders, and particularly to improvements therein for removing the objectionable products of condensation carried over from the burning tobacco. When tobacco is burned in any kind of smoking implement destructive distillation occurs and in addition to the carbon dioxide and the smoke, various tarry products, nicotine and other vaporizable products are carried over as a vapor. Some of these vaporizable products are condensed to liquids while passing through the stem and mouthpiece, and these liquids in the bore of the mouthpiece and stem are commonly but erroneously assumed to be saliva which has entered through the mouthpiece. These condensed products are drawn into the mouth to some extent along with the unden-20 sioned vapor products, and it is these products of condensation from the vapors created by destructive distillation which largely produce the biting bitterness on the tongue and the ill effects which follow smoking. Various attempts have been made to remove such objectionable products of condensation but the devices heretofore utilized for that purpose have not removed all of the condensed products and have furthermore been difficult to clean, too expensive to manufacture or required too many changes in the pipe construction.

It is an object of this invention to provide an improved pipe or cigar or cigarette holder which will be exceptionally efficient and effective in removing the objectionable substances carried over from the burning tobacco; which will be exceptionally simple and inexpensive in construction; which may be readily manufactured with minimum alteration in present pipe manufacture; which may be readily cleaned without soiling the hands and which may be applied to pipes of various shapes and designs.

Various other objects will be apparent from the more detailed description which will be given.

According to this invention it is proposed to cause the smoke to traverse a path that is longer than the path usually followed in pipes and other implements heretofore manufactured and to deflect the smoke from a straight path and to give the vapors a centrifugal motion whereby all particles of condensed products are thrown off by deflection and centrifugal action. To accomplish this

a baffle tube is inserted in the cooling chamber of the implement which tube gives the vapors a centrifugal swirl. This baffle may be conveniently formed of a piece of tubing made from some ductile material such as aluminum which tubing has a portion of its length flattened and twisted into spiral formation. It has been found desirable to have this baffle tube fit snugly within the bit of the implement and freely within the cooling chamber so that upon disassembling the implement the tube will remain in the bit portion and may be used as a scraping device to clean the corroded parts of the smoking implement. An aperture is cut in the bit end of the baffle tube to allow the cleansed and cooled vapor to be drawn into the mouthpiece. The hole may be placed a short distance in from the end of the tube so as to leave a well or trap for the collection of any products of condensation.

A more detailed description will now be given in connection with the drawings in which:

Fig. 1 is a longitudinal section of a pipe constructed in accordance with this invention;

Fig. 2 is a side elevation partly in section of a disassembled pipe made in accordance with this invention;

Fig. 3 is a plan of the baffle tube;

Fig. 4 is a section taken on line 4—4 of Fig. 3; and

Fig. 5 is a fragmentary section of a modified form of this invention.

For purposes of illustration this invention is shown as applied to a smoking pipe having a bowl 1 with the usual combustion cavity 2 and provided with a stem projection 3, the passage 4 of which communicates with the lower part of the bowl cavity 2. A mouthpiece 5 is removably fitted into an enlarged passage 6 or tenon bore forming the cooling chamber as is usual in pipe constructions. The bore 6 instead of having a length corresponding approximately to the length of the entering tenon 7 of the bit or mouthpiece 5 continues for a considerable distance toward the bowl cavity 2 and connects with the passage 4 so as to provide a cooling and trap chamber for a purpose which will appear presently.

A baffle tube 8 is fitted snugly into the inner end of the bore 9 of the mouthpiece and extends loosely into the entire cooling chamber 6. The greater portion of the length of the

tube is flattened as at 10 and is given a spiral twist, the degree of flattening depending upon the diameter of the tenon bore of the particular pipe or implement into which the 5 baffle tube is to be fitted, the greater the degree of flattening resulting in a larger width to the flattened portion. A small aperture 11 is bored or otherwise formed near one end of the remaining tubular portion of the tube 10 so that smoke from the cooling chamber may enter the bore 9 of the mouthpiece. In assembling the pipe this aperture is always placed facing upwardly in order to eliminate any possibility of tobacco juice running into 15 the bore 9. Between the twisted portion 10 and the hole 11 and adjacent to the aperture two intersecting channels or corrugations 12 are cut or formed upon the flat portion to conduct away any products of condensation 20 that may have collected on the tube and which otherwise would have a tendency to run into the aperture 11 whenever the implement is raised with the bowl portion higher than the mouthpiece. These channels or corrugations 25 will be termed deflectors.

In the modified form as shown in Fig. 5 the center portion only of the baffle tube is flattened and twisted leaving the two ends tubular, one end extending into the bit portion 30 and the other end extending into the passage 4 leading into the bowl. In this form of the invention a second aperture 13 is cut into the forward tubular end of the baffle tube to allow smoke to pass from the passage 4 35 into the chamber 6.

In use the products resulting from burning the tobacco will be drawn into chamber 6 where they will strike the spiral baffle 10. This baffle will direct the smoke along a swirling path and any products of condensation 40 will be thrown off due to the centrifugal force and also due to the deflection of the path of the vapors. It has also been found that the baffle tube is very effective to catch and col-

lect upon the surfaces any particles of tobacco 45 that may be drawn into the cooling chamber due to the baffle being covered with a sticky condensation product to which the particles adhere. Because of the extended path, the deflection and the centrifugal action a cooler and sweeter smoke is realized at the mouthpiece. It has also been found that when the pipe is disassembled for cleaning purposes 50 that the extended end of the baffle tube can be conveniently used as a scraper to clean the corroded parts of the pipe and it is obvious that the tube itself may be readily cleaned 55 by the application of the usual pipe cleaners. The tubes may be made very cheaply from standard tubing and need very few operations 60 upon them to form the completed baffle tube.

It will be obvious that various changes in the details which have been herein described by way of illustration may be made by those skilled in the art within the principle and 65 scope of the invention as defined in the following appended claims.

I claim:

1. A baffle tube for smoking implements comprising a single tube having a tubular 70 portion with an aperture therein and having a flat spirally twisted portion with intersecting deflectors therein.

2. A smoking implement comprising a tobacco chamber, a cooling chamber, a passage 75 connecting said chambers, a mouthpiece attached to said cooling chamber and a baffle tube within said cooling chamber and extending from the mouthpiece to said connecting passage, said tube having a flat spirally twisted portion and a tubular portion, said tubular portion having an aperture therein and said flattened portion having diverging deflectors 80 therein.

In witness whereof, I hereunto subscribe 85 my signature.

EDWIN CALDWELL.
